UNITED STATES PATENT OFFICE.

EDWARD E. CLEMENT, OF WASHINGTON, DISTRICT OF COLUMBIA, ASSIGNOR TO EDWARD F. COLLADAY, OF WASHINGTON, DISTRICT OF COLUMBIA.

RADIO RECEIVING INSTRUMENT FOR SYSTEMS OF BROADCAST DISTRIBUTION.

Application filed June 18, 1924. Serial No. 720,870.

My invention relates to subscribers' station circuits and apparatus for combined telephone and radio telephone systems in which current is supplied to the radio-telephones as well as the telephones over a common system of wired lines. It has for its object to render the supply of energy to the subscriber's radio-telephone constant whether his telephone is in use or not, and is in the nature of an improvement over the invention described and claimed in my prior copending applications Serial No. 581,829, filed August 14, 1922, Patent No. 1,522,357, granted January 6, 1925, and Serial No. 699,023, filed March 13, 1924. Where the usual centralized battery is employed in a telephone system, a constant potential is maintained on the lines, and when the telephones are not in use, the radio-telephones can be adjusted so as to function properly on the telephone current, using the metallic circuit only, without substation grounds; but it is desirable to compensate for the change in potential when a telephone transmitter of low resistance is bridged across the line, especially with respect to the filament current taken over that line. As disclosed in the earlier of the two applications referred to, a cut off relay is provided at the subscriber's station, which becomes energized when the telephone is in use, to disconnect the normal charging circuit from the line to the radio telephone storage battery. In the second application a bridged arrangement of both instruments is resorted to, the plate and filament circuits being in parallel, with resistance interposed in the filament circuit. In the present case I employ a combination of the principles thus disclosed, using bridging circuits without grounds, and compensating resistance which will automatically regulate the voltage and the current in the filament circuit when the telephone is in use.

Other objects will sufficiently appear from the detailed description hereinafter.

My invention is illustrated in the accompanying drawings, in which

Fig. 1 is a diagram of a subscriber's station containing a telephone and a radio telephone receiver, with common battery supply over the line from a central office, and automatic compensating resistance device associated with the radio telephone.

Fig. 2 is a side view of a telephone desk

stand showing a fixed switchhook mounted thereon to hold the radio telephone receiver, and also showing elements of the radio telephone housed in the base of the desk stand.

Fig. 3 is a diagram similar to Fig. 1 showing a modified circuit in which a fixed compensating resistance is employed, with a relay in the telephone circuit, acting to cover and uncover said resistance according to the condition of use or disuse of the telephone.

Fig. 4 is a similar diagram of another modification showing a variable compensating resistance, and a controlling relay therefor similar to that shown in Fig. 3.

Fig. 5 is a similar diagram showing the same compensating resistance as in Fig. 4, but with the controlling relay bridged and operating as a potential relay across the line.

Referring to Fig. 1 of the drawings, 1 and 2 are line wires leading from a telephone central office to the telephone subscriber's station T. At the central office end of the line suitable terminals are supposed to be provided, and a bridged source of current shown as a battery B feeding into the line through typical choke coils b—b. The usual voltage in manual telephone exchanges is 22. The usual voltage in automatic telephone exchanges is 50, where electromagnetic switching is relied upon, and in the present case all the circuits shown and described have been tested on voltages ranging from 22 to 50, with entire success. Unless otherwise stated, however, in this application the battery B may be assumed to deliver from 22 to 25 volts at its terminal. It need scarcely be said that the choke coils b—b are individual to the lines whenever the battery busses are connected thereto, these coils representing either cord circuit relay or repeating coil or choke coil units, or line relay windings normally included when the line is not in telephone use. Under all conditions, a steady flow of current not exceeding 350 milliamperes may be assumed as within good practice, over the ordinary telephone lines, including paper cables. A

larger current than this can be drawn through ordinary lines up to say 1 half ampere, without violating the underwriters' requirements, but in such case special provision must be made for preventing operation of the ordinary "sneak-current" or

heat coil arresters, which are usually set at not to exceed 350 milliamperes for a limited time. The tube V employed in the radio telephone set shown in Fig. 1 is supposed to 5 take only 60 milliamperes in its filament circuit, and a negligible amount in its plate circuit. As a matter of fact, when the tests were made on these circuits, the best results were attained with a filament current not exceeding 50 milliamperes.

Bridged across the wires 1-2 is the telephone T, having a transmitter *t*, a receiver *r*, switchhook *h*, supplemental hook *h'*, carrying the radio telephone receiver *r'*, a 15 ringer *r* and a 2mf condenser *C*³. Extending from the telephone terminals to the radio telephone set are wires 3-4. Wire 3 goes to the primary of the induction coil *I'*, from which wire 5 extends to the tickler coil 6 20 and thence to the plate *p* of the detector tube V. It should be stated that wire 1 goes to the positive or plus side of battery B and wire 2 to the minus or negative side; hence the connection of the plate *p* of the 25 scribe's vacuum tube is correct, being to the positive side of battery. Wire 3 is also connected to wire 5^a through a compensating resistance *s-s'* to the filament rheostat *rh* of the tube V. The filament *f* is connected on 30 its other side to the wire 9 and thence back through wire 4 to the No. 2 or negative side of line. The compensating resistance *s-s'* is controlled by means of plunger core *s²* working in the solenoid S, which is included in series in the filament circuit. The 35 connections are such that the larger the current in the circuit the more resistance is automatically uncovered by the rise of the plunger *s²*, the smaller the current below 40 normal the less resistance will be included. The coil S has a secondary function, in that it offers impedance and thereby chokes any sudden rise of current in the filament circuit, which might otherwise flash and 45 damage the filament before sufficient resistance could be cut in to protect it.

On its input side, the tube V has its grid circuit connected as usual through a grid condenser and a grid leak to the secondary 50 coil *i* of the coupler coil I connected to the antenna circuit 7-8. *C'* is the tuning condenser for the antenna circuit, and *C²* the corresponding condenser for the input circuit.

55 The operation of this circuit of Fig. 1 is as follows: Through an ordinary line of approximately 1 mile to 1½ miles long, the potential available at the telephone terminals is from 18 to 20 volts, which is sufficient for the radio telephone circuits, both plate and filament, using a detector and telephone head set only. With the telephone in the position of disuse as shown in the drawing, the full voltage and full current supplied over the line are available for the

radio telephone. If the telephone receiver *r* is taken down for use, however, during use of the radio telephone, it will be observed that a direct bridge of low resistance is put across the line by way of the wire 1^a, 70 winding *i²* of the induction coil I, switchhook *h*, and telephone transmitter *t*. This draws enough current from the line to cause a decided drop in potential, which must be compensated for, especially in the filament 75 circuit of the radio telephone. In Fig. 1 this is done by means of the resistance *s-s'* regulated in the flow of current in the solenoid S. When the potential drops, the current flow becomes smaller, the core *s²* falls and the resistance in the filament circuit is cut down. When the telephone receiver is again hung up, and the telephone circuit is opened, full voltage will be restored to the wires 3-4, and there will be a 80 rise of current in circuit 5^a, *s-s'*, S and *f*. The resulting energization of coil S will allow the core *s²* to cut in more resistance, and at the same time will automatically 85 choke the rise of current to protect the filament. 90

Fig. 3 contains substantially the same elements and functions in substantially the same manner as the circuit of Fig. 1, except that the compensating resistance in this 95 case is a fixed resistance *rh'*, in series with the choke coil *b'* in the filament circuit 5^a. This compensating resistance *rh'* is covered or shunted when the telephone is taken off the hook by means of relay R whose windings are included in series with the telephone transmitter *t*, and whose armature when pulled up closes the local short circuit 5^b. In order that the windings of R shall not offer undue impedance to the voice 100 waves originated in transmitter *t*, I provide a shunting condenser *C*⁴ of ample size for 105 low or voice frequencies, as for example 2mf.

Referring to Fig. 4, substantially the same 110 circuit is shown therein as illustrated in Fig. 3, the controlling relay R being in series with the telephone transmitter and shunted by a talking condenser; the compensating resistance *rh²* having taps taken off and connected to contacts of a switch *s³* by which the amount of resistance cut in or out by the relay R may be regulated. In this figure the telephone parts are simplified, the switchhook being shown as a small manual 115 switch for convenience.

Fig. 5 shows a modification of the circuit in Fig. 4, in which the controlling relay R' has its windings bridged directly across the line wires 1-2. The relay R in the preceding figures, being a series relay, is low wound, but in the case of the relay R' which is a bridging relay, it is necessary to make its windings of very high resistance, as for example 2500 ohms or even higher. A 130

switch S' is provided by means of which the circuit of relay R' and the circuit of the tube filament f may be closed and opened. The relay opens and closes a shunt around the resistance rh^2 and rh , as before, and it will be noted that as this relay lets go, when the telephone is taken down for use, its armature closes on a back contact, while the armature of the corresponding relay in Fig. 4 closes on the front contact. In other words, the relay R of Fig. 4 pulls up on current in the telephone transmitter circuit; while the relay R' in Fig. 5 is shunted by the telephone transmitter circuit and lets go its armature.

15 What I claim is:

1. In a combined telephone system and radio telephone system, a pair of line wires, a central office source of current supply for said line wires, a subscriber's telephone connected to said line wires, a subscriber's radio telephone also connected to said line wires, means for supplying current from said central source to either or both of said instruments over the line wires, and automatic 25 means for regulating the amount of current supplied to one instrument when the other is in use, said regulating means being directly responsive to changes in current flow due to change in relative resistance in the two 30 instrument circuits and acting thereupon to produce a compensating change in the resistance of the radio telephone circuit.

2. The system described in claim 1 in which the regulating means consist of a 35 solenoid relay having a moveable core, and a rheostat adjustable by said core in its movement, said rheostat and the windings of said solenoid being included in series in the current supply circuit of the instrument 40 to be regulated.

3. The system described in claim 1 in which the regulating device is a relay adapted to vary the amount of resistance in the

current supply circuits of the radio telephone, and having the flow of current in its 45 own windings determined in the use of the telephone.

4. The system described in claim 1 in which the regulating device includes a relay adapted to have its current supply varied 50 when the telephone transmitter is bridged across the line, and an adjustable rheostat controlled thereby.

5. The system described in claim 1 in which the regulating device includes a relay 55 adapted to have its current supply varied when the telephone transmitter is bridged across the line and arranged to adjust a variable resistance in proportion to the current in the relay winding. 60

6. The system described in claim 1 in which the regulating device includes a relay adapted to have its current supply varied when the telephone transmitter is bridged 65 across the line, and adapted to cover and uncover resistance in the radio telephone circuits to compensate for the drop due to the bridging of the said transmitter.

7. A combined telephone and radio telephone instrument comprising a desk standard and base, a telephone transmitter and receiver connected to said desk standard, a movable switchhook adapted to support the receiver and operable by the weight thereof to open and close the telephone circuits, and radio telephone receiving apparatus including a vacuum tube mounted inside the base of said desk standard, together with a rheostat for said vacuum tube and an opening through the base to expose the tube from without, whereby the rheostat may be adjusted and the effect therefor will be visible 75 to the operator. 80

In testimony whereof I hereunto affix my signature.

EDWARD E. CLEMENT.
